CUTTING TOOL

Robert J. Hood, East Hartford, Conn., assignor to
Eastern Tool Company, Inc., East Hartford, Conn.,
a corporation of Connecticut

Filed Aug. 24, 1967, Ser. No. 8,368

Term of patent 14 years

Int. Cl. D8—02

U.S. Cl. D8—98

FIG. 1

FIG. 2

FIG. 5

FIG. 3

FIG. 6

FIG. 4

FIGURE 1 is a perspective view of a cutting tool of the present design.

FIGURE 2 is a top plan view of the tool shown in perspective in FIGURE 1.

FIGURE 3 is a side elevation view of the cutting tool of FIGURE 1 taken from the side opposite to that shown in FIGURE 1.

FIGURE 4 is a bottom plan view of the cutting tool of FIGURE 1.

FIGURE 5 is an end elevation taken from the right hand side of FIGURE 3.

FIGURE 6 is a cross-sectional view, taken along line 6—6 of FIGURE 3, of the present design.

The present design is characterized by the concave shape of the opposite vertical sides of the central portion of the tool body.

I claim:

The ornamental design for a cutting tool, substantially as shown and described.
